(57) **CLAIM**

The ornamental design for a dual fuel carrier, as shown and described.

DESCRIPTION

FIG. 1 is a perspective view of the dual fuel carrier showing our new design;

FIG. 2 is a top view thereof;

FIG. 3 is a front plan view thereof;

FIG. 4 is a side view thereof;

FIG. 5 is a rear plan view thereof;

FIG. 6 is a second side view thereof; and,

FIG. 7 is a bottom plan view thereof.

The broken line showing of fuel tanks is included for the purpose of illustrating and forms no part of the claimed design.
